(57) **CLAIM**

The ornamental design for an office privacy booth, as shown and described.

DESCRIPTION

FIG. 1 is a front, top, right perspective view of a first embodiment of an office privacy booth embodying the new design;

FIG. 2 is a front, top, right perspective view of the office privacy booth of FIG. 1 with the roof in an exploded configuration and the door removed;

FIG. 3 is a front, bottom, left perspective view of the office privacy booth of FIG. 1;

FIG. 4 is a front, top, right perspective view of the office privacy booth of FIG. 1 with the door removed;

FIG. 5 is a front elevational view of the office privacy booth of FIG. 1 with the door removed;

FIG. 6 is a rear elevational view of the office privacy booth of FIG. 1;

FIG. 7 is a left elevational view of the office privacy booth of FIG. 1 with the door removed;

FIG. 8 is a right elevational view of the office privacy booth of FIG. 1 with the door removed;

FIG. 9 is a top elevational view of the office privacy booth of FIG. 1 with the door removed;

FIG. 10 is a bottom elevational view of the office privacy booth of FIG. 1 with the door removed;

FIG. 11 is a cross-sectional view of the office privacy booth of FIG. 1 taken along the cut-plane 11-11 of FIG. 9;

FIG. 12 is a cross-sectional view of the office privacy booth of FIG. 1 taken along the cut-plane 12-12 of FIG. 9; and,

FIG. 13 is a cross-sectional view of the office privacy booth of FIG. 1 taken along the cut-plane 13-13 of FIG. 9.

The broken lines in the drawings depict portions of the office privacy booth that form no part of the claimed design. The Dot-dash lines in the drawings represent the bounds of the claim and form no part of the claimed design.

1 Claim, 12 Drawing Sheets
